UNITED STATES PATENT OFFICE.

KARL GUNNAR MAGNI, OF LINKOPING, SWEDEN.

TACHOMETER.

Application filed February 21, 1924, Serial No. 694,444, and in Sweden April 6, 1923.

The device herein described is intended to make known by acoustic signals whether a machine, for instance a separator, is driven with the right speed. The device is most 5 suitable for a low number of revolutions 50-100 rev/min.

The invention is clearly illustrated in the accompanying drawings, in which:—

Fig. 1 is a rear elevational view of the 10 invention,

Fig. 2 is a vertical longitudinal section view partly in elevation, and

Fig. 3 is an enlarged transverse sectional 15 detail of a modified form of sounding member.

Similar characters of reference are applied to corresponding parts throughout the several views.

As may be seen in Fig. 1 of the accompanying drawing, the tachometer consists principally of a turnable member *a* on which are arranged a bell *b* or such like, a pendulum, consisting of a swingably hung tongue or hammer *c* and a carrier *d*, which forces 25 the tongue to participate in the rotation of the member *a* but which in a certain position permits the same to fall against the bell. The tongue thus makes an oscillation or a part thereof as a result of the action of the 30 force of gravitation. As long as a certain angular velocity is not exceeded the tongue *c* will hit the bell once during each revolution, the bell during the swinging movement of the tongue moving for instance to a substantially vertical position. If said angular 35 velocity is exceeded the swinging velocity of the tongue is increased, it is true, but not in proportion to the number of revolutions. The tongue for that reason turns back to the carrier *d* before it has reached the bell.

The device thus fulfills its purpose in that it rings the sounding member when the speed of the machine exceeds a certain value and ceases to ring when the speed falls below 45 a certain value.

By moving the bell *b* or the carrier *d* in a suitable way, for instance along an arc, concentric to the pivot of the tongue, and fixing it in the new position it is possible 50 to adjust the device for the desired number of revolutions. The same result may be obtained by lengthening or shortening the pendulum or tongue *c*.

The sheet member *a* is to be fastened by 55 being jammed firmly under the nut of the crank pin of a hand driven separator, (not

shown), and the projections *i* are to be bent around the crank. The bell *b* is fastened to the shaft *f*, the peg of which is journaled in the sheet member *a* and is kept into contact with it by means of a spring *g*, which catches into two (or one or more) grooves in the peg. On the shaft *f* is swingably hung a pendulum or hammer *c*, formed as a bow, both ends of which are provided with holes and threaded on to the shaft. The bell *b* is provided with a pin *h*, against which the hammer may beat. The pin may be exchanged for a shoulder or a projection extending from the rim of the bell, which projection is turned inward, as shown in Fig. 3. Out from the sheet member *a* is pressed a spring *d*, which acts as a carrier for the hammer *c*. The bell with the pin *h* may be turned solely together with the spring *g*, 75 whereby the point of said spring slides over depressions or grooves in the sheet member (see Fig. 2) and is held in one of them, when the turning is ended. The pin *h* may thus be fixed in different positions in relation to the parts *a* and *b*, that is, the tachometer may be adjusted for the desired 80 number of revolutions, as stated before.

In the embodiment shown the carrier may be provided with a cushion *e* or such like of 85 elastic or soft material on the points where it is contacted by the hammer.

Having now described my invention, what I claim as new and desire to secure by Letters Patent is:

1. A tachometer for rotatable machine members comprising a rotatable member adapted to partake in the rotation of the machine member, a carrier on said rotatable member, a sounding member secured to the rotatable member, the bell being turnable and fixable in different positions in relation to the rotatable member and the carrier, a swingable pendulum with the swinging center situated at the central part of the bell, 100 a shoulder mounted on the bell to stop the pendulum and transmit the strokes of the pendulum to the bell, the pendulum alternately resting against the carrier and alternately performing a falling movement relative to the carrier approximately in its own plane of rotation in order to hit the shoulder of the bell rotating with the carrier.

2. A tachometer in accordance with claim 1, wherein the sounding member is in the form of a bell, a tubular shaft on the rotatable member, a grooved peg carried by the

bell and turnably mounted in the shaft, and a resilient member engageable with the grooves in the peg for retaining the bell in position.

5. 3. A tachometer in accordance with claim 1, adapted to be mounted on a hand crank, wherein the rotatable member is in the form of a frame provided with a hole for engage-

ment about the hand crank of the machine, and bendable projections extending from the frame adapted to be bent around the crank for attaching it firmly thereto.

In witness whereof, I have hereunto signed my name.

KARL GUNNAR MAGNI.
